O. J. WALINSKY

HAND BAG

Filed Nov. 26, 1927

Fig. 2. OSSIP JOSEPH WALINSKY

BY *Howard P. King*
ATTORNEY

UNITED STATES PATENT OFFICE.

OSSIP JOSEPH WALINSKY, OF SEA GATE, NEW YORK, ASSIGNOR TO MORRIS WHITE INC., OF NEW YORK, N. Y., A CORPORATION OF NEW YORK.

HAND BAG.

Application filed November 26, 1927. Serial No. 235,838.

This invention relates to hand bags, and more particularly illustrated in connection with hand-bags such as are generally carried by women for containing money, hand-5 kerchiefs, trinkets and various small articles, but the invention is not to be understood as confined to any one type of hand bag, the one shown being for illustrative purposes only.

- 10 The objects of the invention are to provide an improved hand bag having increased strength and durability; to provide a practical assembly of a pouch with a celluloid frame or other non-crimpable frame; to reinforce the celluloid; to provide a floating engagement with the means for holding the re-enforcement in the celluloid frame; to avoid a multiplicity of rivets or the like; to enable use of the same type of frame to 15 be utilized with any one of a variety of materials constituting the pouch; to enable the use of machine clamping of the material; to secure rapid and easy assembly of the pouch to the frame; to minimize the operations of 20 securing the parts together; to avoid addition of any bulk to the present-day frame; to secure simplicity of construction and operation; and to obtain other advantages and results as may be brought out in the following description.

Referring to the accompanying drawing in which like numerals of reference indicate similar parts throughout the several views:—

Figure 1 is a side elevation of a hand bag embodying my invention, one end portion of the bag being broken away for disclosing the mode of attachment of parts;

Figure 2 is an end view of the bag;

Figure 3 is an end view of the pouch before the frame is applied;

Figure 4 is a fragmentary face view of one end portion of the bag, looking at the far frame, a portion thereof being broken away;

Figure 5 is a vertical sectional view perpendicular to the general plane of the bag, taken on line 5—5 of Figure 4, showing one of the retaining pins; and

Figures 6, 7 and 8 are sectional views of 50 the upper part of the bag, showing successive steps in the assembly of the bag.

In the specific embodiment of the invention illustrated in said drawing, the reference numeral 1 indicates the pouch in general, which, by virtue of the invention, may

be of any desired material, such as hide of one sort or another, cloth or silk, and so on. This pouch provides the usual opening, the edge of which is secured in a frame 2 of suitable material, such as celluloid, and any number of other non-crimpable materials of which bag frames are now made, and in any plain or fanciful shape which the manufacturer may make through preference or otherwise. Bags of this general type have heretofore been made, that is, bags having pouches the opening of which has its margin secured in a frame, and I accordingly deem it within the limits of my invention to employ any of these old types, shapes or styles of pouches and frames as may meet the desires or needs of the interested parties. For purposes of clarity, I have shown herein in a rather conventional type of bag, very commonly used and simple in design, the frame comprising essentially a pair of U-shaped members hinged together on a common axis at the ends of the legs of the U-members. These U-shaped members, on the edges thereof facing inwardly of the U, are provided with grooves, as heretofore, designed to receive the marginal edge of the opening of the pouch 1. These grooves have been identified herein by reference numerals 3. In the manufacture of celluloid frame bags as carried out heretofore, the edges of the pouch have been glued, riveted and otherwise attached in these grooves, but with varying degrees of insecurity, for glue dries and fails to hold, rivets tear the pouch material, and so on.

By the present invention, before the pouch is applied to the frame, I attach a piping to the edge which is to be secured to the frame, one design of piping 4 being illustrated herein and shown as substantially of a diamond shape in cross-section with one of the acute corner edges cut away admitting the marginal edge of the pouch, as clearly shown in Figure 6. Thereafter, the opposite sides of the piping are pinched or crimped toward each other, thereby securely gripping or clinching the pouch material and holding it for substantially the entire length of the said edge, (see Fig. 7). Next, 10 the edge of the pouch with the attached piping is inserted in the groove of the non-crimpable frame as shown in Figure 8, and held therein by suitable means, such as a retaining pin 5.

In manufacture, the piping 4 is preferably of metal and has sufficient inherent rigidity as to maintain a permanent gripping hold upon the material of which the pouch is composed regardless of the thickness or other characteristics of that material. Hence, I am enabled to permanently secure silk, leather, and a variety of other materials comprising the pouches to the same type of frames with no likelihood of pulling loose in spots or tearing the material. In practice, likewise, the pouch and piping are so cut and proportioned as to enable the piping to be inserted entirely within the grooves of the frame, and properly shaped so as to slide into place very readily. By virtue of the cross-sectional shape of the piping, a very considerable strength may be secured by a comparatively light metal, and I find in practice that no other fastening is required than to just hold the piping at the ends of the U-legs from sliding out of the grooves. However, I may employ as many retaining pins 5 as found desirable or necessary. By use of retaining pins at the ends of the U-legs of the piping, beneath the ends of the same, I avoid the necessity of holes through the piping, and am also enabled to perform the drilling operation on the frame for the holes to said pins before assembly of the pouch in the frame, although it is to be understood that this drilling may be performed after assembly if preferred.

Hand bags have been previously made employing a piping on the pouch material, that piping being held in a frame of crimpable or bendable material, such as metal. However, such construction was not discovered as applicable in connection with frames of non-crimpable or breakable materials, such as celluloid and other materials which cannot be bent without breaking or being otherwise injured. My invention accordingly includes the discovery of the adaptability of instrumentalities to secure certain results. I have discovered a way to permanently secure a pouch material to a celluloid or non-crimpable frame. My means furthermore includes a floating engagement between the celluloid frame and the metal piping, as the pins 5 are shown beneath the ends of the piping which abuts thereagainst. Thus the connection is not so rigid that a blow, such as dropping the bag, would cause the celluloid to chip, crack or break at the pin. The celluloid is accordingly re-enforced by the piping with practically no danger of the pin causing the celluloid to crack or break. The piping, or inner frame 4, not only abuts the pins, but is also held in abutting contact with the walls of the groove of the outer or non-crimpable frame so as to have a certain amount of possible movement when the frame is under an abnormal stress enabling the outer frame to bend slightly with respect to the inner frame.

Obviously other detail changes and modifications may be made in the construction, assembly and use of my improved hand bag, and I do not wish to be understood as limiting myself to the exact construction shown or described except as set forth in the following claims when construed in the light of the prior art.

Having thus described the invention, I claim:

1. A construction of the character described, comprising a grooved frame of breakable material, a pouch, a piping of crimpable material clinching the margin of said pouch, said crimpable piping being inserted in the groove of said breakable frame in floating engagement therewith, whereby the ends of said crimpable piping are floatingly engaged in abutting relation to the lateral portions of said breakable frame, and a pin extending transversely through the breakable frame, said piping being in floating engagement therewith.

2. A construction of the character described, comprising a grooved frame of breakable material, a pouch, a piping of crimpable material clinching the margin of said pouch, said crimpable piping being inserted in the groove of said breakable frame in floating engagement therewith, whereby the ends of said crimpable piping are floatingly engaged in abutting relation to the lateral portions of said breakable frame, and a pin extending into said groove beneath said crimpable frame and the said crimpable frame being in abutting engagement with said pin.

In testimony whereof, I have hereunto affixed my signature at New York, county of New York, and State of New York, this 23rd day of November, 1927.

OSSIP JOSEPH WALINSKY.
